Patented Dec. 12, 1922.

2 SHEETS—SHEET 2.

UNITED STATES PATENT OFFICE.

CHARLES W. FETHEROLF, OF WORCESTER, MASSACHUSETTS.

MACHINE FOR AND METHOD OF MAKING PRINTING PLATES.

Application filed October 10, 1921. Serial No. 506,668.

To all whom it may concern:

Be it known that I, CHARLES W. FETHEROLF, a citizen of the United States, residing at Worcester, in the county of Worcester 5 and State of Massachusetts, have invented a new and useful Machine for and Method of Making Printing Plates, of which the following is a specification.

This invention relates to the making of, 10 plates for printing purposes and, although capable of use for engraving on wood blocks and other kinds of materials, it is particularly adapted for the making of half tone plates on metal.

15 The principal objects of the invention are to provide a machine and a method of engraving by which a very large percentage of the cost of making half tone plates, particularly for newspaper work, will be eliminated and by which plates can be produced without the use of expensive apparatus, chemicals, or technically trained workers; to greatly increase their adaptability to various publications; to provide means where- 20 by engraving can be made directly from an object without first producing a fixed picture of it of any kind; to provide for forming the cuts in a plate with the desired depth so as to secure the desired tones in 25 such a way that the same will be capable of being modified within the judgment of the operator as his taste and artistic ability may dictate so that they can be employed to good advantage in making reproductions; to pro- 30 vide a machine which, while making use of well known mechanical expedients, will guide the cutting blade in parallel lines and provide means whereby the depth of the cut can be regulated by the operator as 35 stated above, and to provide an improved 40 form of printing plate having grooves of such shape that there will be no danger of an intended white spot printing in black or making a blur.

45 The invention also involves improvements in details of construction and various combinations of parts of the machine itself.

Reference is to be had to the accompanying drawings, in which—

50 Fig. 1 is a plan of a machine constructed in accordance with this invention, showing it in the act of reproducing or engraving a picture or the like on a type high metal block;

55 Fig. 2 is an end view of the same;

Fig. 3 is a side view of a part of the machine;

Fig. 4 is a sectional view on an enlarged scale on the line 4—4 of Fig. 2;

Fig. 5 is an enlarged sectional view of a 60 metal printing plate formed in accordance with this invention and illustrating the cutting point therein; and

Fig. 6 is a view of a picture divided into zones for use with this invention. 65

In carrying out the method herein disclosed by the machine shown in the drawings, I start either with a drawing, photograph, or picture which is to be reproduced or engraved, or I provide a projectoscope 70 which may be of any ordinary type and will throw its light from an object placed therein and reflect it on a ground glass 11 so as to provide a picture 12 on this plate. If an instrument of that character is not 75 used, the photograph, drawing or other picture which is to be reproduced, is placed in the location occupied by this picture 12. In either case the figure to be reproduced is located in convenient position, preferably 80 on a shelf 13 projecting from a base 14 which constitutes the standard for supporting the machine.

Also mounted on this standard 14 is a table 15 having a supporting block 16 held 85 in position by dowels 16^a so as to permit it to be turned at right angles after parallel cuts have been made over it in one direction. This is provided with a rest 17 at one side and with a pair of adjusting screws 18 90 at the other which are designed to clamp between them a plate 20 which is to constitute the printing plate. When a half tone plate is to be produced this printing plate is located in the position shown in 95 Fig. 1, in which it is diagonally placed on the table. The purpose of this will be understood by those skilled in the art and will be explained later.

The plate 20 preferably is formed of 100 stereotype metal or some other soft composition of lead, tin and antimony or other metals in proper proportion. This in itself is an important improvement constituting a feature of this invention because a plate of 105 such soft metal can be engraved by this machine in a very convenient manner and without the employment of any exhausting force.

On a bracket 21 on the table 15 I place 110

a vertical pivot stud 22 to which is pivoted one arm 23 of a pantograph. This has the usual other arms 24, 25 and 26. The arms 24 and 26 are permanently pivoted together 5 by a stud 27. Three other studs 28 are used to pivot the other arms together in the form of a parallelogram using the perforations 29 with which the several arms are provided to control both the shape and size of the 10 reproduction, as is well understood in that art. The arm 25 is shown as projecting beyond the arm 24 and beyond its pivot 28 and provided with a stylus 30. This stylus can be located at a short distance from the 15 pivot pin or concentric with it if desired. This stylus does not produce any marks but is used to trace the details of the picture.

At the place at which the two arms 24 and 26 are permanently pivoted, there is provided a head 33 having a cutting or engraving tool 34 projecting down from it at an 20 inclination. The head 33 with the blade 34 is designed to be moved up and down by a thumb screw 35. The threaded lower end of 25 this screw extends into a slide 36 below. This is employed to raise and lower the blade 35 to cause it to make a deeper or shallower cut in the surface of the plate 20. The depth is indicated by a center point or 30 indicator head 33 and a graduated wheel 38 fixed on the thumb screw. This wheel is provided with divisions on its circumference marked off numerically or otherwise. I have shown it as having six marks besides 35 the zero. When it is turned around so that the zero point is in registration with the indicator 37, the blade 34 will not cut into the surface of the plate 20, but when it is turned to any other positions, the blade will 40 cut into different depths as will be obvious. The slide 36 has a dove-tailed bottom guiding portion 39 which slides along in a dove-tailed guide 40.

On the end of the machine is a ratchet 45 wheel 41 fixed to a screw shaft 42 journaled below the table. This wheel has a handle or crank 43 for operating it. The rotation of this ratchet advances a yoke 44 through which the screw passes. The ends of the 50 yoke pass upwardly on opposite sides of the machine and carry the ends of the guide 40. Thus, the ratchet wheel slides the guide with head over the plate to be engraved. The guide works in ways 45 on the side edges of 55 the table 15. From what has been said, it will be obvious that the ratchet wheel can be rotated by hand. I have provided a spring pawl 47 locking the ratchet wheel automatically also an operating pawl 48. 60 This operating pawl has a counterbalance 49 for keeping it in contact with the teeth and is pivotally mounted on a bell crank 50 which is provided with a link 51 extending down and supporting a pedal 52. Every 65 time the pedal is depressed the wheel will

be rotated one tooth or more according to its adjustment. The adjustment is secured by means of a screw 53 threaded into the bell crank 50 and passing loosely through a slot in a bracket 54 on the table. This 70 screw has a head 55 and a locking nut 56. This nut secures it in adjusted position on the bell crank and the nut and head together limit the motion of the crank on its pivot. 75

The engraving tool 34 is so shaped as to give considerable more depth to the cut out portions of the engraving plate 20 than is possible on half tones as at present produced. For this purpose it is provided with two lower cutting edges 56, making equal angles with a vertical line at the center preferably. The angle between the two edges preferably is about 60°. It will be seen that this blade will cut in to the plate 20 to 80 any desired depth to form V-shaped grooves 57. These grooves may be only slight as shown at the extreme right and left hand of Fig. 5, or they can be deeper. It is the turning of the head 38 that regulates the 85 depth of the cut and consequently the width of the uncut surface of the plate between grooves 58. It will be observed, therefore, that it is the depth of the two adjacent cuts that regulates the width of the printing surface 58. These printing surfaces, as is well known, constitute the points or lines which receive the ink and impart the impression in printing. Just at the right of the cutting blade in Fig. 5, I have shown two of them 90 which come to a point and therefore produce only a line or dot while farther to the right I have shown one numbered 59 which terminates below the surface of the plate and consequently will not make any impression. In other words, at that point a blank or white space is provided the width of two 95 cuts. 100

The method of producing a half tone plate by this invention is as follows:

A picture or tracing in outline 12 provided as above specified is plotted off into shading areas, each area numbered from 1 to 6 to correspond to the depth of shading existing in said areas. The number 1 would be applied to all very dark or black shaded areas, number 2 to lighter shaded areas, number 3 to a still lighter shade and so on. These areas are outlined either by graphically marking on the picture 12 by a pencil 110 or the like or by simply being kept in the mind of the operator after he is sufficiently experienced. I have shown them marked out on the drawing as a new operator would have to employ them. They are given their respective numbers from 1 to 6, 1 showing the blackest lines with shallowest cuts and 6 the faintest lines with deepest cuts. The plate 20 to be engraved is placed in position 115 diagonally as indicated in Fig. 1 and the 120 pedal 52 depressed. The ratchet wheel 41 is 125 rotated and the engraving tool 34 is caused to 130 pass over the plate 20, the depth of the cut being controlled by the indicator head 33 and the graduated wheel 38.

guide 40 located at the upper corner of it. The operator then takes hold of the thumb screw 35 with one hand and the knurled knob 31 with the other hand and draws the frame 33 with its cutting tool 34 across the plate guided by the guide 40. In doing so, he turns the thumb nut 35 so as to bring any desired one of the numerals into registration with the indicator 37 corresponding to the shading area which the stylus 30 is passing over on the picture. For example, near the top of the picture the stylus will first encounter a pure white spot. The thumb nut is turned so that the numeral 6 registers with the point 37 and the head and cutting tool is started across the guide and cuts a deep groove. The stylus next enters an area marked 2 on the drawing and the thumb nut is immediately turned back to the point 2. Now the blade 34 still cuts into the printing plate but not so deeply. The thumb nut is kept at that point until the stylus 30 reaches a lighter spot when it will be shifted accordingly to correspond to the area as numbered on the figure. When this line is completed the cutting blade is lifted either by hand or automatically as may be desired and the head moved back to the left. Now the operator steps on the pedal 52 which shifts the hand wheel 41 around one or more notches and advances the guide 40 the width of one complete line on the metal printing. This also draws the stylus 30 down a proportionate distance and the operator then again goes through the process above described.

After the whole plate has been engraved with parallel lines making an angle of, say 45°, with the horizontal in this way, the supporting block 16 turned quarter way around and the process repeated if a half tone plate is desired. This produces a plate in which two series of lines run across it diagonally and at right angles to each other.

The gradations of shading of the original picture are reproduced on the plate by variation in the depth and width of the lines engraved thereon but this is not done automatically. The operator has a chance to introduce variations according to his knowledge of the art of printing by half tone plates or according to his artistic ability. It will be understood that the invention is not limited to half tone plates, as plates can be made in which there is only one series of parallel engraved lines and those can be made at the angle above specified or any other angle or vertically as may be desired.

It will be seen, therefore, that the necessity for taking a photograph of some objects that are to be reproduced by means of a half tone plate is done away with by this method and that the use of an expensive photographing outfit and use of chemicals in making the half tone plate itself are also

eliminated. This expands the usefulness of the half tone and other kinds of plates by permitting of their use when no photograph can be obtained and by facilitating their use when one is at hand. In the latter case 70 an indistinct photograph which would not produce a good half tone plate by the old methods can be used as the base for a practical illustration even for newspaper work. This is a very important advantage because 75 many photographs and other pictures cannot be successfully reproduced by the half tone method on account of the large black or blurred or indistinct surfaces which they present.

The plate itself is an important element of the invention because of the ease with which variations in shading not shown on copy or object to be reproduced can be provided. A large white or blank surface cannot possibly be printed black or blur on account of the projection of a soft inking roller on its recessed shallow flat surfaces as has been the case heretofore. Even if the roller has descended in the blank field, 90 nothing will be printed except fine sharp points.

Although I have illustrated and described only a single embodiment of the invention and shown details of a single machine for carrying it out, I am aware of the fact that many modifications can be made therein without departing from the scope of the invention as expressed in the claims. Therefore, I do not wish to be limited to all the 100 details of construction herein shown and described but what I do claim is:—

1. In a machine for making printing plates, the combination of means for supporting a plate, a cutting tool, means for guiding said tool to engrave parallel lines on the plate, and a pantograph having a stylus at one angle for tracing the picture or configuration to be transferred, the tool being located at another angle of the pantograph.

2. In a machine for making half tone plates, the combination of means for supporting a metal plate, means for engraving parallel lines in the plate, and a pantograph having a stylus for tracing the picture or configuration to be transferred, with means for guiding said engraving means to move along parallel lines, and means for moving said guide transversely to its length by a step by step motion.

3. In a device for reproducing a picture or the like on a printing plate, the combination with a pantograph having a stylus adapted to be moved over the shape to be reproduced and a cutting tool for acting on the plate, of a guide for confining the motion of said cutting tool to parallel movements.

4. In a device for reproducing a picture 130

- or the like on a printing plate, the combination with a pantograph having a stylus adapted to be moved over the shape to be reproduced and a cutting tool for acting on the plate, of means for holding the plate in fixed position, a guide for said cutting tool, and means on the pantograph for regulating the depth of the cut of the cutting tool.
- 5 3. In a device for reproducing a picture or the like on a half tone plate, the combination with a pantograph having at one angle a stylus adapted to be moved over the shape to be reproduced and provided at an adjacent angle with a cutting tool for acting 10 on the plate, means for holding the plate in fixed position, and a guide for said cutting tool for restricting its motions, said cutting tool having parallel cutting edges converging to a point, of means for regulating the 15 depth which it projects below the printing 20 surface of the printing plate.
4. In a device for reproducing a picture or the like on a printing plate, the combination with a pantograph having a stylus 25 adapted to be moved over the shape to be reproduced and a cutting tool for acting on the plate, said stylus and tool being located at two adjacent angles of the pantograph, and a guide for said cutting tool, of a head 30 mounted to move along said guide but capable of vertical motion thereon and carrying the cutting tool, and means on said head for raising it and lowering it with respect to the guide.
- 35 5. In a device for reproducing a picture

or the like on a printing plate, the combination with a pantograph having a stylus and provided with a cutting tool for acting on the plate, means for holding the plate in fixed position, a guide, a slide on said 40 guide carrying said cutting tool, a head mounted to move with said slide but capable of vertical motion thereon, a screw on said head for raising it and lowering it with respect to the slide, said screw having a circular head provided with graduations, and a fixed center point on the head for indicating the elevation of the tool by its registration with the graduations.

6. In a machine for making half tone 50 plates, the combination of means for supporting a plate, means for engraving parallel lines in the plate, and a pantograph having a stylus for tracing the picture or configuration to be transferred and a cutting tool for cutting into the plate, with means for guiding said cutting tool to move along parallel lines, and means for moving said guide transversely to its length by a step by step motion, said means comprising a 55 ratchet wheel, a screw fixed to the ratchet wheel, a nut on the guide adapted to be operated by the screw, and means for oscillating said wheel intermittently a step at a time.

60 In testimony whereof I have hereunto affixed my signature.

CHARLES W. FETHEROLF.
